US00D665341S

(12) **United States Design Patent**
Chu et al.

(10) **Patent No.:** US D665,341 S
(45) **Date of Patent:** ** Aug. 14, 2012

(54) **EXTERNAL BATTERY**

(76) Inventors: **Yan-Qiu Chu**, Shenzhen (CN);
Zhong-Wei Sun, Shenzhen (CN)

(**) Term: **14 Years**

(21) Appl. No.: **29/399,438**

(22) Filed: **Aug. 15, 2011**

(51) LOC (9) Cl. **13-02**

(52) U.S. Cl. **D13/103**; D13/108

(58) **Field of Classification Search** D13/102–110,
D13/118–119, 184, 199; D14/250–253,
D14/432, 434; 320/101–102, 107–115, 120;
429/96–100, 149, 159, 163, 176, 177, 186

See application file for complete search history.

(57) **CLAIM**

The ornamental design for an external battery, as shown and described.

DESCRIPTION

FIG. 1 is a perspective view of a external battery showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines / dotted lines / are intended to show features that are environmental only and form no part of the claimed design.

1 Claim, 5 Drawing Sheets

FIG. 1

FIG. 2

FIG. 3

FIG. 4

FIG. 5

FIG. 6

FIG. 7
